UNITED STATES PATENT OFFICE

2,006,855

MINING MACHINE

Herman W. Driehaus, Cicero, Ill., assignor to
Goodman Manufacturing Company, Chicago,
Ill., a corporation of Illinois

Application November 8, 1933, Serial No. 697,141

17 Claims. (Cl. 262—28)

This invention relates to improvements in mining machines of the track mounted type adapted to cut horizontal kerfs in the mine wall adjacent the roof or floor or at intermediate positions with respect thereto.

My invention has among other objects to provide a new and improved machine of the type described, constructed with a view towards utmost efficiency and ease of operation, compactness, ruggedness and adaptability to varying mining conditions and more particularly to provide a counterbalancing means for balancing the machine during the cutting operation when the cutter bar is disposed to one side or the other of the track, together with a new and improved means for tilting the cutter bar for following an uneven mine bottom.

My invention may be more clearly understood with reference to the accompanying drawings wherein:

Figure 1 is a top plan view of one embodiment of my invention with parts broken away and in section to more clearly show the details thereof;

Figure 2 is a partial diagrammatic side elevation of the device shown in Figure 1;

Figure 3 is an enlarged detail partial side elevation of the device shown in Figure 1, with certain parts broken away and in section to more clearly show the details of my invention; and

Figure 4 is an enlarged plan view of the forward portion of the device shown in Figure 1, with parts broken away and in section to more clearly show the details thereof.

Like reference characters refer to like parts throughout the various figures.

Referring now in particular to the drawings, the embodiment of my invention illustrated includes a track 10 supported on track wheels 11, 11 and axles 12, 12. The truck 10 has a turntable 13, disposed adjacent its forward end and extending forwardly of the forwardmost track wheels. The turntable 13 forms a supporting means for a cutting element generally indicated by reference character 14, which cutting element is supported on said turntable for vertical movement and angular adjustment with respect thereto in a manner which will herein-after more fully appear when referring to the novel features of my invention.

The cutting element 14 is similar to that shown in a prior application Serial No. 659,522, filed by William W. Sloane, March 2, 1933, so will only be described in so far as is necessary

to make my present invention clearly understandable. The cutting element 14 includes a motor 15 secured to a cutter frame 16, which cutter frame extends forwardly therefrom and beyond the forward boundaries of the truck 10.

The cutter frame 16 has a cutter head 17 carried thereby for pivotal movement with respect thereto about an axis extending longitudinally of the machine. The cutter head 17 forms a support means for a cutter bar 18, which cutter bar is supported for movement towards or away from the axis of rotation of said cutter head in parallel spaced guides 19, 19. The cutter bar 18 has a cutter chain 20, driven from the motor 15 in a usual manner, and guided for orbital movement thereabout. The cutter bar 18 is pivotally movable with respect to the cutter head 17 about an axis perpendicular to the axis of rotation of said cutter head for adjustment for cutting along a mine bottom or for cutting in intermediate positions between the mine roof and mine bottom in places of narrow width.

A motor 21 is provided on the truck 10 rearwardly of the turntable 13 and cutting element 14. The motor 21 forms a drive means for driving the track wheels 11 for propelling said truck along the trackway at a high speed for transportation or a low speed for sumping the cutter bar into the coal or feeding the cutter bar 18 along the coal face. Another drive, generally indicated by reference character 22 and not herein shown or described in detail, since it is no portion of my present invention, is provided from the motor 21 to the turntable 13 for turning said turntable for positioning the cutter bar 18 for cutting, or swinging said cutter bar across the front of the truck 10 for feeding said cutter bar in an arcuate path across the coal face in the usual manner.

With reference now in particular to several of the novel features of my invention, a pair of relatively widely parallel spaced trunnion supports 23, 23 are provided on the turntable 13 adjacent the forward end thereof. Each trunnion support 23 forms a bearing member for a stud 24, which studs in turn form a pivotal support adjacent their outer ends for frame members 25, 25. The frame members 25, 25 are arranged in parallel relation with respect to each other for pivotal movement about coaxial horizontal axes extending transversely of the turntable 13 and cutting element 14, which axes are disposed adjacent the forward end of the truck 10 and forwardly of the forwardmost

track wheels 12, 12 when said cutting element is so positioned that its longitudinal center line is parallel with the longitudinal center line of said truck.

5 Each frame member 25 has a pair of parallel spaced upstanding guides 26, 26 formed integral therewith adjacent opposite ends thereof. The frame members 25 extend along the turntable 13 adjacent opposite sides thereof and are secured together by means of a C shaped counterbalancing member 27. The C shaped member 27 extends from the rearward end of the frame member 25, 25 along opposite sides of the motor 15 and beyond the rearward end thereof, 10 beyond the turntable 13 and the rearwardmost track wheels 12, 12 a substantial distance, so as to counterbalance the effect of the weight of the cutter head 17 and cutter bar 18 and loads imparted thereto during the cutting operation.

20 The upper portion of the C shaped frame member 27 is in alignment with the upper sides of the frame members 25, 25 so as to obtain a maximum counterbalancing effect from said frame member, and said frame member is formed with hollow portions 28 and 29, 29, which are adapted to be filled with a relatively heavy material such as lead.

25 A counterbalancing member 30 is secured to the turntable 13, adjacent opposite sides thereof and extends rearwardly therefrom. The counterbalancing member 30 is likewise C shaped and conforms substantially to the shape of the C shaped member 27. Hollow portions 31 and 31a are provided in the counterbalancing member 30, which are adapted to be filled with lead or any other heavy material for counterbalancing the weight of the cutter head 17 and cutter bar 18.

30 A suitable means is provided for tilting the cutting element 14 and cutter bar 17 about the axis of the studs 24, 24 and for yieldably holding said cutting element and cutter bar in various adjusted positions with respect to the mine bottom, which as herein shown, comprises an adjusting screw 32, having a collar 33 secured thereto, intermediate its ends. The adjusting screw 32 passes through a bored portion in the counterbalancing member 30 and is yieldably supported by said counterbalancing member by means of a compression spring 34 encircling said adjusting screw and interposed between the underside of the collar 33 and the upper side of the counterbalancing member 30, and a compression spring 35 encircling said adjusting screw and abutting the under side of the counterbalancing member 30 on an opposite side thereof from the compression spring 34. The compression spring 35 is held in engagement with the underside of the counterbalancing member 30 by means of a collar and nut indicated by reference character 37.

35 The upper end of the adjusting screw 32 is threaded within the hub of a worm gear 39, which worm gear is journaled within a suitable casing 40, secured to the C shaped frame 27, adjacent the central portion thereof. A worm 41 on a transverse shaft 42 meshes with the worm gear 39. The transverse shaft 42 is journaled within the casing 40 and is connected at its outer ends to shafts 43, 43 extending angularly with respect thereto in a forwardly direction, by means of suitable universal joints of an ordinary construction. The shafts 43, 43 extend

40 C shaped frame member 27 and extend towards the outer edges thereof and have suitable hand wheels 45, 45 secured to the outer ends thereof for rotating said shafts and the worm 41 and the worm gear 39. Thus the C shaped frame member 27, frame members 25, 25, cutting element 14 and cutter bar 13 may be pivotally moved as a unit about the axis of the studs 24, 24 for adjusting the angle of inclination of the cutter bar 18 with respect to the mine bottom. 10

45 The upstanding guides 26, 26 have racks 46, 46 secured thereto and their inner faces are adapted to be engaged by outer faces of the cutter frame 16. The outer ends of the upstanding guides 26, 26 are abutted by shouldered portions 49, 49 15 formed in the cutter frame 16. Retaining strips 50, 50 are secured to the outer sides of the cutter frame 16 adjacent the shouldered portions 49, 49 and extend inwardly therefrom and abut suitable shouldered portions formed in the outer 20 sides of the upstanding guides 26, 26, permitting the cutter frame 16 and cutting element 14 to be slidably moved along said guides.

50 The racks 46, 46 are engaged by pinions 53, 53 keyed to longitudinally extending shafts 54, 25 54 adjacent opposite ends thereof, which shafts in turn are journaled in the cutter frame 16, adjacent opposite sides thereof and extend parallel with respect to each other. A worm gear 55 is keyed to each longitudinally extending 30 shaft 54. The worm gears 55, 55 are meshed with and driven from suitable worms (not shown), which worms in turn are driven from the motor 15 in reverse directions without reversal thereof in a manner which has been 35 fully described in the aforementioned prior application of William W. Sloane. The worm gears 55, 55 and worms meshing therewith are of the self-locking type, thus permitting the cutting element 14 to be locked in various elevated positions with respect to the turntable 13 when said worms and worm gears are disconnected from the motor 15.

55 In order to keep the height of the machine-down to a minimum and permit a maximum amount of tilting movement of the cutter bar 18 with respect to truck 10, it is desirable that the axis of tilting movement be as close to the forward end of said truck as possible and that the studs 24, 24 be of a relatively small diameter. 50 In order that studs of a relatively small diameter may safely carry the cutting element 14, frame members 25, 25, guides 26, 26 and counterbalancing member 27 during the cutting operation, it is necessary that a means be provided for taking a portion of the load from said studs during the cutting operation and especially while the cutter bar is being fed across the forward end of the truck. Suitable means have herein been provided for taking twisting loads from the studs 60 24, 24 and for preventing twisting of the upstanding guides 26, 26, which comprise vertically extending bearing members 56, 56, extending upwardly from the trunnion supports 23, 23 and having inner faces which abut the outer sides 65 of the upstanding guides 26, 26, and bearing members 57, 57 spaced rearwardly from said first mentioned bearing members and formed integral with and extending upwardly from opposite sides of the counterbalancing member 30. 70 The bearing members 57, 57 have bearing engagement with the outer sides of the frame members 25, 25 rearwardly of the upstanding guides 26, 26.

75 It may now be seen that a new and improved 75

means has been provided for supporting a mining machine cutting element and cutter bar for cutting adjacent the mine floor or roof or at various intermediate positions with respect thereto, 5 which means is so arranged as to take up a minimum amount of vertical and lateral dimensions and permit tilting of the entire cutting element together with the guides which support said cutting element for rectilinear adjustment 10 with respect to the turntable, and that the device of my invention is so arranged that the weight of the cutter head and cutter bar and loads imparted to the machine thereby are effectively counterbalanced in a new and novel 15 manner.

While I have herein shown and described one form in which my invention may be embodied, it will be understood that the arrangement and construction of the various parts thereof may 20 be altered or changed without departing from the spirit and scope thereof. Furthermore, I do not wish to be construed as limiting myself to the precise form illustrated, excepting as it may be limited in the appended claims.

25 I claim as my invention:

1. In a mining machine, a track mounted truck including a truck frame, a cutting element thereon including a projecting cutter bar disposed forwardly of the forward end of said 30 truck frame, and means for supporting said cutting element for vertical adjustment with respect to said truck frame and for pivotal movement with respect to said truck frame about an axis extending transversely thereof including a 35 trunnion support on said truck frame and a pair of parallel space guides pivotally connected to said trunnion support and extending rearwardly therefrom and forming an adjustable supporting means for said cutting element.

40 2. In a mining machine, a wheeled truck adapted to travel along a trackway, a turntable on said truck, a cutting element on said turntable including a motor and a cutter bar disposed forwardly of said motor and projecting 45 beyond the forward end of said truck, and means for supporting said cutting element on said turntable for vertical adjustment with respect thereto and tilting movement in planes inclined with respect to the mine bottom including a support 50 pivotally mounted on said turntable to rock relative thereto about a transverse axis, and guide members extending upwardly from said support and slidably engaging said cutting element.

55 3. In a mining machine, a wheeled truck adapted to travel along a trackway, a turntable on said truck, a cutting element on said turntable including a motor and a cutter bar disposed forwardly of said motor and projecting beyond the forward end of said truck, and means 60 for supporting said cutting element on said turntable for vertical adjustment with respect thereto and tilting movement in planes inclined with respect to the mine bottom including a support pivotally mounted on said turntable to rock 65 relative thereto about a transverse axis, guide members extending upwardly from said support and engaging said cutting element, and means engaging said guide members for moving said cutting element vertically with respect to said truck.

70 4. In a mining machine, a wheeled truck adapted to travel along a trackway including a truck frame, cutting mechanism supported on said truck frame including a motor and a cutter bar disposed forwardly of said motor and

projecting forwardly of the forward end of said truck, means for supporting said cutting element for vertical movement with respect to said truck frame comprising a plurality of guide members extending upwardly from said truck frame and disposed rearwardly of the forward end thereof, and means for supporting said cutter bar for tilting movement with respect to said truck frame about an axis extending transversely thereof comprising means for supporting said guides on said truck frame for tilting movement with respect thereto about an axis extending transversely thereof. 10

5. In a mining machine, a wheeled truck adapted to travel along a trackway including a truck frame, cutting mechanism supported on said truck frame including a motor and a cutter bar disposed forwardly of said motor and projecting forwardly of the forward end of said truck, means for supporting said cutting element for vertical movement with respect to said truck frame comprising a plurality of guide members extending upwardly from said truck frame and disposed rearwardly of the forward end thereof and means simultaneously driven 15 by said motor engaging said guide members for vertically moving said cutting element with respect to said truck frame, and means for supporting said cutter bar for tilting movement with respect to said truck frame about a horizontal axis disposed rearwardly of the rearward end of said cutter bar comprising a trunnion support for said guide members and means for moving said guide members about the axis 20 of said trunnion support. 30

6. In a mining machine, a wheeled truck adapted to travel along a trackway, a turntable on said truck, cutting mechanism supported on said turntable including a motor and a cutter bar projecting forwardly of the forward end of said truck, means for supporting said cutting element for vertical movement with respect to said turntable comprising a plurality of guide members extending upwardly from said turntable, racks carried by said guide members, 40 pinions driven by said motor engaging said racks, and means for supporting said cutter bar for adjustable tilting movement with respect to said turntable about an axis extending transversely of said cutter bar comprising a trunnion 45 support for said guide members on said turntable adapted to form a transverse pivotal support for said guide members, and means for moving said guide members about the axis of said trunnion support. 50

7. In a mining machine, a wheeled truck adapted to travel along a trackway, a turntable on said truck, cutting mechanism supported by said turntable including a motor and a cutter bar projecting forwardly of the forward end of said truck, means for supporting said cutting element for vertical movement with respect to said turntable comprising a plurality of guide members extending upwardly from said turntable, racks carried by said guide members, pinions driven by said motor engaging said racks, and means for supporting said cutter bar for adjustable tilting movement with respect to said turntable about an axis extending transversely of said cutter bar rearwardly of the rearward 65 end thereof but adjacent the forward end of said truck comprising a trunnion support for said guide members on said turntable and means for moving said guide members about the axis of said trunnion support. 70

75

8. A mining machine comprising a track mounted truck having a turntable thereon, a cutting element mounted on said turntable for vertical rectilinear adjustment with respect thereto including a motor, a cutter frame disposed forwardly of said motor, a cutter head carried by said cutter frame for rotatable movement with respect thereto about an axis extending longitudinally thereof and a pivoted chain carrying cutter bar carried by said cutter head for rectilinear adjustment towards or away from the axis of rotation thereof, means for supporting said cutting element for movement towards and away from said turntable comprising a plurality of vertical guide members supported on said turntable, and means for supporting said cutter bar for tilting movement with respect to said truck about an axis extending transversely thereof comprising a support member on said turntable having pivotal supporting engagement with said guide members.
9. A mining machine comprising a track mounted truck having a turntable thereon, a cutting element mounted on said turntable for vertical rectilinear adjustment with respect thereto including a motor, a cutter frame disposed forwardly of said motor, a cutter head carried by said cutter frame for rotatable movement with respect thereto about an axis extending longitudinally thereof and a pivoted chain carrying cutter bar carried by said cutter head for rectilinear adjustment towards or away from the axis of rotation thereof, means for supporting said cutting element for movement towards and away from said turntable comprising a plurality of vertical guide members supported on said turntable, racks carried by said guide members, pinions journaled in said cutter frame and meshing with said racks and a self-locking drive connection from said motor to said pinions, and means for supporting said cutter bar for tilting movement with respect to said truck about an axis extending transversely of said cutter bar comprising means for supporting said guide members on said turntable for pivotal movement with respect thereto about a horizontal axis.
10. A mining machine comprising a track truck having a turntable thereon, a cutting element mounted on said turntable for vertical rectilinear adjustment with respect thereto including a motor, a cutter frame disposed forwardly of said motor, a cutter head carried by said cutter frame for rotatable movement with respect thereto about an axis extending longitudinally thereof, and a pivoted chain carrying cutter bar carried by said cutter head for rectilinear adjustment towards or away from the axis of rotation thereof, means for supporting said cutting element for movement towards and away from said turntable comprising a plurality of vertical guide members supported on said turntable, means for supporting said cutter bar for tilting movement with respect to said turntable about an axis extending transversely of said cutter bar comprising means for supporting said guide members on said turntable for pivotal movement with respect thereto about a horizontal axis, and means for counterbalancing said cutter bar when disposed to one side or the other of the center line of said truck comprising a weighted member extending rearwardly of said turntable and another weighted member extending rearwardly of said turntable and another weighted member extending rearwardly of said guides.
11. A mining machine comprising a track mounted truck having a turntable thereon, a cutting element mounted on said turntable for vertical rectilinear adjustment with respect thereto including a motor, a cutter frame disposed forwardly of said motor, a cutter head carried by said cutter frame for rotatable movement with respect thereto about an axis extending longitudinally thereof, and a pivoted chain carrying cutter bar carried by said cutter head for rectilinear adjustment towards or away from the axis of rotation thereof, means for supporting said cutting element for movement towards and away from said turntable comprising a plurality of vertical guide members supported on said turntable, means for supporting said cutter bar for tilting movement with respect to said turntable about an axis extending transversely of said cutter bar comprising means for supporting said guide members on said turntable for pivotal movement with respect thereto about a horizontal axis, and means for counterbalancing said cutter bar when disposed to one side or the other of the center line of said truck comprising a weighted member extending rearwardly of said turntable and another weighted member extending rearwardly of said turntable and another weighted member extending rearwardly of said guides.
12. A mining machine comprising a track mounted truck having a turntable thereon, a cutting element mounted on said turntable for vertical rectilinear adjustment with respect thereto including a motor, a cutter frame disposed forwardly of said motor, and a chain carrying cutter bar carried by said cutter frame for rectilinear adjustable movement with respect thereto, means for supporting said cutting element for movement towards and away from said turntable comprising a plurality of vertical guide members supported on said turntable and adapted to slidably engage said cutter frame, and means for supporting said cutter bar for tilting movement with respect to said turntable about an axis extending transversely thereof comprising means for supporting said guide members on said turntable for pivotal movement with respect thereto about a horizontal axis.
13. In a mining machine, a truck adapted to be supported on a mine track for movement therealong, a turntable on said truck, a cutting element on said turntable including a horizontal chain carrying cutter bar adapted to cut a kerf in the mine wall by rectilinear movement of the truck along the trackway and by swinging movement across the front of said truck, a cutter frame forming a supporting means for said cutter bar, means for supporting said cutter frame and cutter bar for tilting movement with respect to said truck about an axis extending transversely of said cutter bar and for movement of said cutter frame towards or away from said truck for adjusting the elevation of said cutter bar with respect to the ground comprising a plurality of upstanding guides pivotally connected to said turntable for pivotal movement with respect thereto about a horizontal transverse axis, and means for taking the thrust of said frame upon swinging movement of said cutter bar across the forward end of said truck comprising a plurality of vertically disposed bearing members on said turntable having slidable bearing engagement with said guides.
14. In a mining machine, a truck adapted to

be supported on a mine track for movement therealong, a turntable on said truck, a cutting element on said turntable including a horizontal chain carrying cutter bar adapted to cut a kerf 5 in the mine wall by rectilinear movement of the truck along the trackway and by swinging movement across the front of said truck, a cutter frame forming a supporting means for said cutter bar, means for supporting said cutter frame and cutter bar for tilting movement with respect 10 to said truck about an axis extending transversely of said cutter bar and for movement towards or away from said truck for adjusting the elevation of said cutter bar with respect to the 15 ground, comprising a plurality of upstanding guides formed in the shape of a widely extended polygon pivotally connected to said turntable for pivotal movement with respect thereto about a common horizontal transverse axis disposed 20 adjacent the forward end of said truck, and means for relieving the thrust of said frame from the pivotal connection of said guides to said truck comprising a plurality of bearing members extending upwardly from said turntable adjacent opposite ends of opposite sides 25 of said guide members and having bearing engagement with said guide members.

15. A mining machine comprising a track mounted truck having a turntable thereon, a cutting element mounted on said turntable for vertical rectilinear adjustment with respect thereto including a motor, a cutter frame disposed forwardly of said motor, and a chain carrying cutter bar carried by said cutter frame for rectilinear adjustable movement with respect thereto, means for supporting said cutting element for movement towards and away from 30 said turntable comprising a plurality of vertical guide members supported on said turntable and adapted to slidably engage said cutter frame, and means for counterbalancing said cutter bar when disposed to one side or the other of the center line of said truck comprising a weighted member extending rearwardly of said turntable and another weighted member extending rearwardly of said guides adjacent the upper end thereof. 35

40

45

16. A mining machine comprising a track mounted truck having a turntable thereon, a cutting element mounted on said turntable for vertical rectilinear adjustment with respect thereto including a motor, a cutter frame disposed forwardly of said motor, and a chain carrying cutter bar carried by said cutter frame for rectilinear adjustable movement with respect thereto, means for supporting said cutting element for movement towards and away from 10 said turntable comprising a plurality of vertical guide members supported on said turntable and adapted to slidably engage said cutter frame, and means for counterbalancing said cutter bar when disposed to one side or the other of the center line of said truck comprising a weighted member extending rearwardly of said turntable and another weighted member extending rearwardly of said guides adjacent the upper end thereof. 15

HERMAN W. DRIEHAUS.

CERTIFICATE OF CORRECTION.

Patent No. 2,006,855.

July 2, 1935.

HERMAN W. DRIEHAUS.

It is hereby certified that error appears in the printed specification of the above numbered patent requiring correction as follows: Page 3, first column, line 36, claim 1, for "space" read spaced; and page 4, first column, line 49, claim 10, before "truck" insert the word mounted; and that the said Letters Patent should be read with these corrections therein that the same may conform to the record of the case in the Patent Office.

Signed and sealed this 27th day of August, A. D. 1935.

Leslie Frazer
